UNITED STATES PATENT OFFICE.

JOSEPH N. WARNER, OF ST. PAUL, MINNESOTA.

CHANGE-MAKING MACHINE.

No. 833,568.

Specification of Letters Patent.

Patented Oct. 16, 1906.

Application filed November 18, 1905. Serial No. 288,002.

To all whom it may concern:

Be it known that I, JOSEPH N. WARNER, of St. Paul, Ramsey county, Minnesota, have invented certain new and useful Improvements in Change-Making Machines, of which the following is a specification.

The object of my invention is to provide a machine which will automatically make change, allowing the clerk or operator to deliver the proper change to a customer making a purchase without having access directly to the coins.

A further object is to provide a machine which will be rapid in its computation and operation and absolutely correct, whereby the frequent mistakes made by clerks and cashiers in making change will be avoided.

The invention consists generally in a change-making machine which will add the items of purchases and deduct them from the cash deposited or received from the customer and deliver the difference in change.

Further, the invention consists in air-distributing valves whose operation controls the admission of air to the mechanism for ejecting the coins from their cylinders.

Further, the invention consists in rotary change-making valves.

Further, the invention consists in means for throwing the carrying mechanism to its operative or inoperative position.

Further, the invention consists in a quarter or twenty-five-cent piece valve.

Further, the invention consists in providing cylinders having means operated by a fluid-pressure for ejecting the articles therefrom.

Further, the invention consists in bill-receptacles and controlling-valves therefor.

Further, the invention consists in a revolving shaft having a series of cam-surfaces and mechanism controlled by the revolution of said shaft for operating the change-making valves; and, further, the invention consists in various constructions and combinations, all as hereinafter described, and particularly pointed out in the claims.

In the accompanying drawings, forming part of this specification, Figure 1 is a sectional view on the line *a a* of Fig. 2. Fig. 2 is a side elevation of the machine with the casing on one side removed, showing the interior construction. Fig. 3 is a transverse vertical sectional view on the line *b b* of Fig. 1, showing the rotary and slide valves and the space in which the perforated bill or card is placed.

preparatory to the operation of the machine. Fig. 4 is a front elevation of the machine. Fig. 5 is a detail view illustrating the normal inoperative position of the air-controlling valve and the mechanism connected therewith for throwing the change-making valves back to zero. Fig. 6 is a detail view of the air-controlling valve, showing its lever thrown to its extreme position in one direction to admit air to the distributing-valve casing and return the change-making valves to zero. Fig. 7 is a vertical sectional view of the air-controlling valve, taken on the section-line *c c* of Fig. 10. Fig. 7^a is a detail sectional view of the air-controlling valve in its normal inoperative position. Fig. 7^b is a similar view illustrating the initial movement of the air-controlling valve to admit air to the engine and to the piston for operating the bill or card clamping mechanism. Fig. 7^c illustrates the position of the valve to which it is automatically moved when air is admitted to the coin-delivering cylinders. Fig. 7^d is a detail sectional view showing the position to which the valve is moved to admit air to the bill-receptacle cylinders to close the same and open the engine and the piston connected with the bill-clamping mechanism to the exhaust. Fig. 7^e is a sectional view through the valve-casing, showing the air-supply port near the periphery of the valve in its stem or axis. Fig. 7^f is an edge view of the air-controlling valve removed from its casing. Fig. 8 is a similar view on the section-line *d d* of Fig. 10. Fig. 9 is a sectional view on the line *e e* of Fig. 10. Fig. 10 is a horizontal sectional view on the line *f f* of Fig. 7. Fig. 11 is a side elevation of the distributing-valve casing partially broken away to show the air connection established through one of the slide or reciprocating valves when it is operated. Fig. 12 is a vertical sectional view through the distributing-valve on the line *g g* of Fig. 3. Fig. 13 is a plan view of the upper fixed plate in the distributing-valve casing. Fig. 14 is a horizontal sectional view on the line *h h* of Fig. 15. Fig. 15 is a vertical sectional view of the upper or top fixed plate on the line *i i* of Fig. 13. Fig. 16 is a bottom view of the upper plate. Fig. 17 is a horizontal sectional view of the upper valve on the line *j j* of Fig. 18. Fig. 18 is a vertical sectional view of the upper valve on the line *k k* of Fig. 17. Fig. 19 is a plan view of the lower valve. Fig. 20 is a vertical sectional view of the lower-valve plate on the line *l l* of

Fig. 25. Fig. 21 is a vertical sectional view on the line *m m* of Fig. 19. Fig. 22 is a plan view of the bottom plate. Fig. 23 is a horizontal sectional view on the line *n n* of Fig. 20 looking in the direction of the arrow. Fig. 24 is a horizontal sectional view on the line *o o* of Fig. 20. Fig. 25 is a horizontal sectional view on the line *p p* of Fig. 20. Fig. 26 is a plan view of the bottom plate and the reciprocating or slide valves, illustrating their relative position. Fig. 27 is a similar view showing the slide-valves in position to admit air into the horizontal ducts on the receiving or deposit side and also illustrating in dotted lines the position of the cam when the clutch is thrown into operation. Fig. 28 is a similar view illustrating the position of the slide-valves when ready to admit air into the lengthwise ducts on the purchase side and also showing the position of the cam when air is admitted through the lower valve to operate the clutch. Fig. 29 is a plan view, partially in section, showing the position of the valve-changing clutches and their connections when air is exhausted from the engine and ready to be turned to zero by the operation of the air-controlling lever. Fig. 30 is a detail plan view illustrating the mechanism connected with the clutches of the coin-changing valves and the position of the same when the engine starts and the operation of the machine begins. Fig. 31 is a transverse sectional view on the line *q q* of Fig. 30. Fig. 32 is a detail plan view of a portion of the mechanism connected with the coin-changing valves. Fig. 33 is a sectional view on the line *r r* of Fig. 30. Fig. 34 is a sectional view on the line *s s* of Fig. 30. Fig. 35 is a detail sectional view on the line *t t* of Fig. 31. Fig. 36 is a detail sectional view on the line *u u* of Fig. 34. Fig. 37 is a detail view of a portion of the lever mechanism for turning the coin-changing valves back to zero. Fig. 38 is a front view of the total-registering device with the cover raised, showing the dials. Fig. 39 is a sectional view on the line *v v* of Fig. 31. Fig. 40 is a front elevation of the change-making valves, showing them in their zero position. Fig. 41 is a sectional view of the registering device on the line *w w* of Fig. 30. Fig. 42 is a view of the change-making valves, illustrating their position when a deposit of twenty dollars has been made. Fig. 43 is a similar view illustrating the position assumed by the valves when a purchase of five dollars and fifty-two cents has been made. Fig. 44 is a sectional view of a peculiar arrangement of valve employed for controlling the discharge of quarters or twenty-five-cent pieces from the machine. Fig. 45 is a horizontal sectional view of the same. Fig. 46 is a detail view of the mechanism between the cam-shaft which controls the travel of the coin-changing valves and the cylinder from which the clutch for starting

and stopping the said valves is operated. Fig. 47 is a view of the cam-shaft and the mechanism connected therewith on the line *x x* of Fig. 1. Figs. 48, 49, 50, and 51 are detail sectional views of the cam-shaft and its connections. Fig. 52 is a detail sectional view illustrating the oscillating shaft and arm which bears on the surface of the cam-shaft. Fig. 53 is a vertical sectional view through the governor-valve which controls the passage of air to the rock-shaft cylinder. Fig. 54 is a plan section view of the coin-ejecting mechanism. Fig. 55 is a transverse vertical sectional view illustrating the bill-receptacle and the mechanism for operating the same. Fig. 56 is a partial plan view of the same. Fig. 57 is a detail view of the valves for controlling the flow of pressure to the bill-receptacle-operating mechanism. Fig. 58 is a front view of the same. Fig. 59 is a transverse vertical sectional view of the casing wherein the valves for controlling the passage of air to the bill-receptacle-operating mechanism are arranged. Fig. 60 is a transverse vertical sectional view of the coin-cylinders and their operating mechanism. Fig. 61 is a detail sectional view showing one of the coin-cylinders in its tilted filling position. Fig. 62 is a sectional view on the line *y y* of Fig. 61. Fig. 63 is a vertical sectional view on the line *z z* of Fig. 65. Fig. 64 is a front elevation of a coin-cylinder. Fig. 65 is a transverse section of Fig. 64. Fig. 66 is a plan view of the bill or card which the clerk punches to indicate the total cash received and the items of purchases.

In the drawings, 2 represents a base, and 3 a suitable casing inclosing the operating parts of the machine. (See Figs. 1, 2, and 3.)

The air-controlling valve.—4 is a casing wherein a rotary air-controlling valve 5 is arranged, Sheets 5 and 6. A tube 6 communicates with the valve 5 and with a suitable source of air under pressure. (Not shown.) The valve 5 has an annular recess 7 communicating with the air-supply tube and with a port 8, and the said valve has also an annular groove 9 extending partially around the same and communicating with an exhaust-port 10 which extends through the axis of the valve to the open air. An operating-handle 11 is mounted on the valve-stem and provided with an arm 12, projecting substantially at right angles therefrom for the purpose hereinafter described. The casing 4 is provided with ports 13 and 14, leading to the ends of a cylinder 16, and as the valve is rotated the port 8 will alternately register with the ports 13 and 14 and admit air to the cylinder 16, Fig. 8. Tubes 17 and 18 communicate with the valve 5 and also with the ports 13 and 14, so that when air is admitted to either of said ports it will simultaneously enter one of the tubes 17 or 18, according to the position of the rotary valve, 130

Fig. 9. The cylinder 16 has a piston 19 connected to a rocking lever 20, which has a forked inner end adapted to engage pins 21 on a stud 22, centrally arranged on a cap 23. A plate 24 is attached to said cap, and between said cap and plate a chamber 25 is formed, which communicates at all times with the air-supply through a tube 26, Figs. 1 and 12. The oscillation of the lever 20 will impart a vertical movement to the cap 23 and the plate 24, the casing and a shoulder 27 on a fixed plate 28 acting as guides during such movement, Fig. 3. The oscillation of the lever 20 and the consequent movement of the plate 24 are accomplished by moving the air-controlling valve to the position shown in Fig. 7^b and admitting air beneath the piston 19, whereupon the plate 24 will be forced down upon the plate 28 beneath. Upon moving the air-controlling valve to the position shown in Figs. 9 and 7 the space beneath the piston 19 will be open to the exhaust, and the pressure will be admitted above the piston to raise the plate 24 to its normal position.

The air-distributing valves.—Referring to Sheet 9, the top plate 24 is shown provided with a series of longitudinal ducts 29, 30, 31, and 32 on one side of the middle line of the plate, and each duct has a port 33, 34, 35, and 36 extending through the top of the plate and a series of ports 37, 38, 39, and 40 extending downward through the bottom of the plate. Upon the opposite side of the middle line of the plate a corresponding number of longitudinal ducts are provided, which I will indicate by the same reference-numeral, using the exponent "a," and these last-named ducts have ports leading through the top and bottom of the plate and corresponding to those described, and I will indicate them also by the same reference-numerals, with the addition of the exponent "a." These longitudinal ducts are connected at one end by tubes 41, 42, 43, and 44, and 41^a, 42^a, 43^a, and 44^a, with the clutches which control the operation of the change-making valves, as will hereinafter appear. There are four of these ducts on each side of the center, designated 50 for the cents, tens of cents, dollars, and tens of dollars, the ducts on one side being used in connection with the amount of money received or the deposit for the purchase and those on the other side for the items of purchases, Figs. 13 and 14.

Upon the plate 24 and inclosed thereby and the cap 23 is a rotating valve 45, having a stem 46, which projects up through the stud 22 and carries a gear 47, which meshes 60 with an idle gear 48, driven from a pinion 49 on the upper end of a shaft 50, that is journaled in a bracket 51 and the base of the machine. (See Figs. 1 and 3.) A worm-wheel 52 is mounted on said shaft, meshing with a similar worm-wheel 53 on a horizontal shaft

54, that is geared to an engine 55 of the double-cylinder type and operated by air-pressure from the tube 18. (See Fig. 1.) A crank 56 is provided on the shaft 54, and a pitman 57 connects the said crank with a cross-head 58, slideable in a guide 59. The valve 45 is geared to the shaft 54 in the ratio of four to one, and consequently there will be four revolutions of the shaft and eight movements of the cross-head to one complete revolution of the valve 45. The valve 45 is provided with a port 60, terminating on its under side in a groove 60', Fig. 17, and this valve rests upon the plate 24 and revolves thereon, and its port is arranged to register 75 successively with the ports in the plate 24, leading to the horizontal ducts therein, and, as heretofore stated, there being pressure at all times in the air-chamber 25 and upon this rotary valve. Consequently as the valve revolves and its port coincides with the ports in the plate beneath air-pressure will flow successively into each of the longitudinal ducts and from thence through the tubes connected therewith to the change-making-valve 80 clutches. The valve is also provided with a port 61, Figs. 13, 14, and 15, extending therethrough and arranged to coincide, just as the valve completes its revolution, with a port 62, leading to a tube 63, which communicates 95 with the change-making valves, as will hereinafter appear. Annular concentric grooves 64 and 65 are also provided in said valve, the former in the same circle as the port 60 and the latter as the port 61, and communicating, 100 respectively, with exhaust-passages 66 and 67, which extend up through the stem of the valve to the open air, Figs. 3 and 17. By means of these grooves and passages the ports in the plate 24, over which the valve 105 rotates, will be on the exhaust except when they are in communication with the ports 60 and 61.

The plate 28 is provided with rows of perforations 68, 69, 70, and 71 on one side of its middle line and corresponding rows of perforations 68^a, 69^a, 70^a, and 71^a on the other side, extending through the plate from top to bottom, Figs. 3 and 26. This plate has a flat upper surface, between which and the bottom 115 of the plate 24 the bill or card 72 (shown on Sheet 18) is clamped and securely held during the operation of the machine, the pressure being sufficient to prevent the escape of air around the edges of the bill. This bill, as 120 shown on Sheet 18, is rectangular in form and provided on one side of its middle line with four blank rows, designated as for cents, tens of cents, dollars, and tens of dollars, and each row containing a series of circles 73, which 125 are punched out or perforated to indicate the sum of money received from the customer when the purchase is made. Upon the other side of the middle line of the bill a corresponding number of blank rows are provided, 130

containing a greater number of similar circles, which are punched out to indicate in dollars and cents the items of purchases. The longitudinal rows on each side of the bill 5 are divided transversely into nine spaces, the circles in the different spaces representing in the first row one cent up to and including nine, in the second row ten cents up to and including ninety cents, in the third row one 10 dollar to nine dollars, and in the fourth row ten dollars to ninety dollars, making it possible, therefore, with this machine to make 15 change for any sum up to one hundred dollars. The circles 73 are arranged to coincide with the ports in the bottom of the plate 24 and with the vertical perforations in the plate 28, and consequently when the circles 20 are perforated the air-pressure will flow therethrough from the longitudinal ducts in the plate 24, but will only flow from such 25 ducts as communicate with perforations in the card. In other words, although air will be admitted to all of the longitudinal ducts successively as the valve 45 revolves, it will not pass from them down through the ports in the plate 28 unless the card is perforated above these ports.

Beneath the plate 28 and spaced therefrom 30 is a lower fixed plate 74, supported on a base 75 and having guides 76, whereon the plate 28 rests and through which said plate 28 is secured by suitable means to said plate 74. (See Fig. 3.) The fixed plate 74 (see Sheet 8) is provided with longitudinal ducts 77, 78, 35 79, and 80 on one side of its middle line and corresponding ducts 77^a, 78^a, 79^a, and 80^a on the other side of its middle line. Ports 81 and 82 are provided, leading from the ducts, respectively, through the top of the plate, 40 there being four cross-rows of ports on each side of the middle line, one row for each duct, and there being as many ports in each longitudinal row as there are in the fixed plate 28 and as many ports as there are circles in the 45 bill or card 72.

Between the guides 76 on the plate 74 I provide sliding or reciprocating valves 83 and 84, each provided with a single transverse row of perforations 85, arranged to register 50 with the successive rows of perforations in the plates 28 and 74 and temporarily forming communicating passages between them and conducting the air from one to the other, provided the circle is punched in the card above. (See Figs. 3, 11, and 26.) If there happens 55 to be no perforations in the longitudinal row in the card coinciding with the row of the fixed plates, then, although the perforations in the sliding valves 83 and 84 will furnish communication between the ports of the fixed plates, no passage of air will take place. The ends of the valves 83 and 84 are secured 60 to the cross-head 58, and as this cross-head makes eight movements to one revolution of 65 the valve 45 it follows that the sliding or re-

ciprocating valves 83 and 84 will move four times in one direction between the ports of the plates 28 and 74 and four times in the other direction with each revolution of said valve, and during these four movements, which are timed, of course, to correspond with the coinciding of the rotary-valve port with the ports in the plate 24, there will be opportunity for the air-pressure to pass through the fixed plates and the sliding valves, assuming, of course, that perforations are made in the card 72 for such passage.

The bottom of the plate 74, Sheet 8, is provided with a series of ports 87, 88, 89, and 90, communicating with the ducts 77, 78, 79, and 80 and with similar ports 87^a, 88^a, 89^a, and 90^a, leading, respectively, to the ducts 77^a, 87^a, 79^a, and 80^a, the first four of these ports communicating with the perforations when made on the received side of the card 72 and the last four ports communicating with the perforations when made on the purchase side of the bill or card. A rotary valve 91 is provided beneath the plate 74 and arranged to bear thereon, Figs. 12, 19, 20, and 21, being yieldingly held by the spring 92 and having a stem 93 supported in bearings 94 and provided with a gear 95, corresponding to a gear on the upper rotary valve and driven in the same manner and at the same speed from the shaft 50. This lower valve is provided with ports 95 and 96, Fig. 19, the former being arranged to register successively with the ports 87^a, 88^a, 89^a, and 90^a and communicating with the perforations in the purchase side of the card 72 and with the duct 97, leading to an annular groove 98, which communicates with a tube 99, extending to the cylinder 100. The port 96 is arranged to register successively with the ports 87, 88, 89, and 90 to establish communication between the perforations in the card and a passage 101, leading to a duct 102, from which a tube 103 extends to the cylinder 100. This cylinder, Figs. 46 and 47, is provided 100 with two chambers 104 and 105, having pistons 106 and 107 connected by a stem 108 and arranged to operate a clutch 109 on a shaft 110. A spring 111 normally holds the clutch in its inoperative position; but when 105 air is admitted to either one of said chambers said clutch will be operated to lock a loosely-mounted gear-wheel 112 on said shaft. A star-wheel 112' is secured to said gear-wheel, and a spring-pressed pin 112" engages said 110 star-wheel and prevents accidental movement of said gear-wheel.

The cam-shaft and its connections.—The shaft 110, Figs. 1, 46, and 47, is provided with a pinion 113, meshing with a gear 114 on one end of a shaft 115, the other end of said shaft being provided with a beveled gear 116, meshing with a similar gear 117 on a shaft 118, on which an arm 119 is splined and adapted to slide back and forth, and pro- 125 130

vided with lugs 120, between which the end of a bracket 121 on the cross-head 58 is loosely fitted to permit the free oscillation of the shaft and said arm. A shaft 122 is arranged parallel to the shaft 118 and is provided with a series of cam-surfaces varying in width, extending from one end of the shaft to the other in the form of steps, there being a cam-surface for each denomination of coin represented by the circles on the bill inserted into the air-distributing valve. A yoke 123 (see Fig. 2) is secured at each end on the shaft 118 and arranged to bear on the arm 119 and press an antifriction-wheel 124, carried by said arm, against the cam-surfaces on the shaft 122. (See Figs. 2 and 46.) One end of the yoke 123 is provided with an upwardly-extending arm 125, (see Sheet 15,) to which a spring 126 is attached, the tension of which tends to rock the shaft 118 and force the yoke 123 against the arm 119 and compel the said arm to follow the cam-surfaces on the shaft 122. The cam-shaft 122 has a revolving back-and-forth movement in its bearings, and to time this movement with the operation of the air-distributing valves I provide a pinion 127 on said shaft, meshing with a gear 128 on a shaft 129, which extends under the shaft 118 and is provided with a pinion 130, meshing with the teeth of the rack-bar 131, attached to the cross-head 58 and operating in a guide 132. (See Figs. 1 and 47.) This rack-bar will have the same stroke or travel as the sliding valves 83 and 84, moving four times in one direction and four times in the other direction with each complete revolution of the air-distributing valves, and the gears between the rack-bar and the shaft 122 are arranged to revolve the cam-shaft twenty-two times in one direction with each half-stroke of the rack-bar and twenty-two times in the opposite direction during the other half of each stroke of the rack-bar. These twenty-two revolutions of the cam-shaft are arbitrary, being fixed by the desired number of movements of the oscillating arm on the cam-surfaces. For instance, in the bill 72 (see Fig. 67) there are four circles to receive the perforations in the cents-column, and consequently the cam-surface for that column must have a proportionately greater width, or area, so that the roller 124 traveling thereon will have a continuous uniform movement while the sliding valves are passing four circles representing the cents-column in the bill. The remaining cam-surfaces are so proportioned in area according to the number of circles in the bill. In the first cam-surface (marked 1, Fig. 1) the shaft will make four revolutions while the roller is traveling over this surface. In the next three it will make two revolutions each, and in the fifth will make four, in the sixth two, the seventh two, the eighth two, and the ninth two, or a total of twenty-two revolutions each time the roller 124 is moved lengthwise of the shaft 122. These cam-surfaces I have marked from 1 to 9, but do not design them for cents or dollars alone, as they are used interchangeably with either, according to the position of the perforations in the bill. The revolution of the cam-shaft and the travel of the roller 124 thereover as the cross-head 58 is reciprocated will impart a rocking movement to the shaft 118, the degree and continuance of such movement depending upon which cam-surface the roller 124 happens to be in contact with. If it is bearing on one of the higher cam-surfaces, the arc described by the rock-shaft 118 will be longer than when the roller is in engagement with one of the lower cam-surfaces, and the rocking will continue for a longer period on a wide surface than it will on a narrow one, and the rotary movement of the change-making valves will be varied accordingly. During the first half of the revolution of the cam-shaft the cam-surfaces will operate to press the roller away from the shaft and rock the shaft 118 toward the cam-shaft, causing a corresponding movement to be imparted to the gear 114 and the pinion 113 and operating the proper change-making valve to indicate the amount received or the deposit, the spring 126 holding the roller 124 snugly against the cam-surfaces during the revolution of the shaft.

To hold the roller against the cam-surfaces when it is traveling from the low to the high side thereof and the valves are adding the items of purchases, I prefer to provide an arm depending from the yoke 123 and pivotally connected by a link 134 with a piston 135, operating within a cylinder 136, having inlet and exhaust ports 137 and 138. (See Figs. 48, 49, 50, and 51.) An eccentric 137 is loosely mounted on one end of said cam-shaft and has a semicircular recess 137' to receive a pin 138' on said shaft. An eccentric-strap 138'' incloses said eccentric and is yieldingly held thereon by springs 138''. A slide-valve 139 is connected with a crank 140, mounted on said eccentric-strap, and has annular grooves 141, adapted to coincide alternately with said inlet and exhaust ports during the revolution of the cam-shaft. A tube 142 leads from the air-supply tube 18 and has a branch 143 communicating with the inlet-port 137. (See Sheet 15.) When the parts are in the position shown in Fig. 48, the revolution of the cam-shaft toward the left will move the valve 139 to the position shown in Fig. 49 and open the cylinder to the exhaust, and there will be no resistance to the entrance of the cylinder into the piston while the antifriction-roller is traveling from the low to the high side of the cam-surfaces. In Fig. 50 the piston 136 has reached the limit of its stroke in one direction, the antifriction-roller is on the high side of its cam-surface, 130

- and continued revolution of the cam-shaft in the same direction will move the valve 139 toward the left and open the air-inlet port and close the exhaust, whereupon the pressure will force the piston toward the right and hold the arm 125 and its roller against the cam-surfaces while passing from the high to the low sides thereof. When the cam-shaft is revolved in the opposite direction, 5 the operation described will be repeated, air being admitted to the cylinder 136 only while the piston therein is moving toward the right or when the roller 124 is traveling from the high to the low side of the cam-surfaces.
- 10 15 To provide for an increase in the air-pressure in the cylinder 136 during the time the roller is traveling from the high to the low side of the cam-surfaces, I provide a casing 144 in the tube 142, having a passage 145, 20 with which the pipe 99 communicates. A port 146 leads from the passage 145 to a valve 147, which is vertically movable in said casing and is normally held in its raised position by a spring 148. The stem of this 25 valve has an annular groove 149, which communicates with a passage 150, leading to the tube 142. The pressure of the spring 148 normally holds the valve 147 in a position to partially close the passage through the duct 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930
- The operation of the cam-shaft controls the entrance of air into the chambers 104 and 105 of the cylinder 100. To accomplish this, I provide on the cam-shaft an eccentric and strap device 151, corresponding to the one described with reference to Figs. 48-50, 40 and an arm 152, pivotally connected to a crank 153 on a rock-shaft 154, provided with a crank 155, pivotally connected with a slide-valve 156. (See Figs. 1, 46, and 52.) This slide-valve has a series of four annular 45 grooves 157, and the chambers 104 and 105 have inlet and exhaust ports 158 and 159, respectively, said inlet-ports communicating with the tubes 99 and 103 and arranged to admit air into the chambers 104 and 105 in 50 the rear of the pistons therein to operate the clutch 109 and temporarily lock the gear 112 on its shaft. The grooves 157 are so arranged that when one of the chambers is taking air the inlet-port leading to the other 55 chamber will be on the exhaust, and as the cam-shaft revolves the inlet and exhaust ports of the chambers 104 and 105 will be alternately opened and closed. Through the 60 rocking of the shaft 118 and the gears connected therewith the shaft 110 will be con-
- tinuously oscillated during the operation of the machine; but the gear 12 being loose on said shaft 110 no power will be transmitted from the said shaft until the clutch 109 is operated, and this takes place only when the bill or card is perforated either on the receiving or purchase side and the pressure of air passes therethrough to the sliding valves and the lower rotary valve beneath. The clutch 109 controls, therefore, the operation of the 70 change-making valves. The clutches on the shafts of the change-making valves are all operated successively as the air-pressure is distributed through the tubes leading from the ducts over which the upper rotary valve 80 operates; but no movement of the change-making valves will take place in either direction until the clutch 109 has been operated to lock the gear 112. These change-making valves and their connections I will now describe in detail.
- The change-making valves.—Referring to Sheets 10 and 11, 160, 161, 162, and 163 represent four horizontal parallel shafts supported in bearings on brackets 164 and 165 90 and carrying loosely-mounted gears 166, arranged to mesh successively with one another in series, the first one of the four meshing with an idle gear 167, driven from the gear 112. On the other end of each of the 95 said shafts a circular disk is secured, which I will term hereinafter as the "change-making valve," operating in a vertical plane in either direction, according to the direction of movement of its shaft, and designated, respectively, by reference-numerals 168, 169, 170, and 171 and representing cents, tens of cents, dollars, and tens of dollars. (See Figs. 40, 42, and 43.) A recess 172 is provided within a casing 173, wherein the said valves rotate. 100 These change-making valves are each provided with holes or perforations 168^a, 168^b, and 168^c, 169^a, 169^b, and 169^c, 170^a, 170^b, and 170^c, and 171^a, 171^b, and 171^c, arranged in four concentric circles, the two inner circles of holes 168^a of the cents-valves representing cents, the next outer circle 168^b two cents, and the outside one, 168^c, five cents, and these holes are also arranged on radial lines or rows, there being nine rows containing from one to four holes, according to their location, and separated from one another by ten spaces on the face of the valve; so that ten successive steps in the movement of the valve will cause its complete revolution. The 110 holes 169^a, 169^b, and 169^c are correspondingly arranged in their valve and designate: the inner circle 169^a, ten cents; the next two 169^b, twenty cents each, and the outer circle 169^c fifty cents. The holes 170^a, 170^b, and 170^c 120 and 171^a, 171^b, and 171^c are also arranged in concentric circles and on radial lines in their valves and are designated as the "dollars" and "tens-of-dollars" holes.
- The holes in the change-making valves 130

represent numerals from "1" to "9" around the valves. For instance, in the cents-valve the first hole on the right of the zero position indicates one cent and is in the inner circle of 5 holes. The second hole on a radial line is in the third circle from the center and represents two cents. In the third radial row there are two holes, one in the inner circle and one in the third from the center of the 10 valve, representing a total of three cents. In the fourth radial row there are three holes representing two one cent and one two cents, or a total of four cents. On the next radial line there is one hole in the outer circle representing 15 five cents, and so on around the valve, the last radial line or row having a hole in each of the four circles and representing a total of nine cents. The other valves have their holes arranged the first to represent tens of 20 cents from ten to ninety; the second, dollars, from one dollar to nine dollars, and the third or the fourth and last one of the whole series having its holes arranged to represent tens of dollars from ten dollars to ninety dollars.

25 The holes in the cent-valve are so located that as the valve revolves the nine radial rows will successively register with fixed ports 174, 175, 176, and 177, arranged one above another in the casing 173 opposite the 30 valve. (See Figs. 31 and 39.) These ports are connected with tubes 178, 179, 180, and 181, which lead to the coin-cylinders, as will be hereinafter described in detail. The other valves have similar ports and tubes, which I 35 will designate by the same references, with the addition of the exponent "a," "b," and "c" for the respective valves.

On the opposite side of the change-making valves from the ports leading to the coin-cylinders is a passage 182, extending transversely 40 with respect to said ports and communicating with any one or all of them and the tubes leading therefrom when the valves are properly set for such communication. When the 45 valves are in their zero position, as the first three are shown in Fig. 42 and all of them in Fig. 40, the flow of air through the ports from the passage 182 will be cut off. The passage 182 is connected to the tube 63 to conduct 50 the air-pressure from the port 62 to the change-making valves. As the gears 166 are locked on their shafts, the change-making valves will be rotated forward or back, according to the position of the roller 124 on 55 the cam-shaft, assuming that the clutch 109 has been operated to lock the gear 112. To lock the gears 166, I provide a clutch 183, splined on each of the shafts 160, 161, 162, and 163, Fig. 31. These clutches are operated 60 by means of arms 184, mounted on stems 185, having pistons 186 and 187 within chambers 188 and 189 of cylinders 190, located beneath each of the parallel shafts. Springs 191 normally hold these pistons at 65 the rear end of their chambers and the

clutches 183 out of engagement with the gears 166.

Upon the shafts 161, 162, 163 star-wheels 192, 192^a, and 192^b are splined, Figs. 30, 31, and 32, each wheel having ten teeth, and on 70 the shafts 160, 161, and 162 bull-teeth 193, 193^a, and 193^b are splined. The hubs of these bull-teeth are provided with annular grooves 194 to receive the ends of arms 195, 195^a, and 195^b, said arms being pivoted on the machine-frame at a point intermediate to their 75 ends and attached to and operated by bars 196, arranged beneath each of the change-making valve-shafts and whereon the arms 184 are mounted. The movement of the 80 bars 196 when air is admitted to either of the pistons 186 and 187 will oscillate the arms connected therewith and move the bull-teeth along their shafts out of engagement with the star-wheels. For instance, if air is 85 admitted to the cylinder controlling the clutch for operating the tens-of-dollars valve-gear the arm 195^b will be oscillated and the bull-tooth 193^b moved out of engagement with the star-wheel 192^b, as shown in Fig. 32, 90 and the shaft 163 and its change-making valve can then be revolved in either direction without affecting the other valves.

In case one of the preceding valve-gears is 95 locked on its shaft to cause the operation of its valve then the bull-tooth of the next preceding shaft will be made inoperative, while the position of the bull-tooth meshing with the star-wheel on the succeeding shaft will remain unchanged. The carrying operation 100 from one valve to the succeeding one will therefore be uninterrupted, while the connection between a valve-shaft and the preceding one is temporarily broken during the 105 operation of each valve. Obviously it will only be necessary to have star-wheels on the last three shafts of the series and bull-teeth on the first three to obtain the desired carrying movement from one valve to the next and to break the connection temporarily between each valve and the preceding one.

In order that the star-wheels may all be properly lined up preparatory to the operation of the machine, I provide a plate 197, having three forked arms which straddle the 110 hubs of the star-wheels, as shown in Figs. 30, 31, and 34. The plate 197 is mounted on the stem 198 of a piston 199, that is slidable in a cylinder 200. A spring 201 normally holds the said piston in a retracted position, and the cylinder in the rear of said piston is connected to the pipe 142, so that when air is admitted to the engine to start the machine it will flow through the tube 142 into the cylinder 200 and actuate the piston therein and 115 the plate 197 to line up all the star-wheels preparatory to the operation of the machine.

Referring to Sheet 14, and particularly Figs. 42 and 43, I have shown the valves in Fig. 42 in the position they would assume 120

when a twenty-dollar deposit has been made. When the clerk or operator receives the twenty dollars, he will punch the bill in the circle representing that amount, as shown in Fig. 67, and also punch the items of purchases, in this case amounting to five dollars and fifty-two cents, and insert the bill into the valve, and as the upper rotary distributing-valve revolves air will be admitted to the cylinder controlling the clutch for said tens-of-dollars valve and temporarily lock its gear, and as the cam-shaft revolves and rocks the shaft 118 the roller 124 passes from the low to the high side of "2" cam and the air passes down through the lower rotary valve and operates the clutch 109, the gear mechanism will be set in operation, and the valve representing the tens of dollars will be moved two steps toward the right from its zero position, as shown in Fig. 42. Then as the rotary valve passes over the cent-port on the purchase side the cents change-making valve will be operated and moved two steps toward the right from its zero position, as indicated in Fig. 43. During this movement the bull-tooth 193 will move the star-wheel 192 and the ten-cent change-making valve one step toward the left, and in so doing the bull-tooth 193^a will move the star-wheel 192^a and the dollar-valve one step toward the right, and the bull-tooth 193^b will move the star-wheel 192^b and the tens-of-dollars valve one step toward the left. Then as the rotary valve passes over the tens-of-cents port and the air passes through the fifty-cent perforation in the card the ten-cent change-making valve will be moved five more spaces toward the left, or six in all from its original zero position as shown in Fig. 43, the star-wheel 192 being, as heretofore explained, temporarily out of engagement with the bull-tooth 193, so that the cent-valve will not be affected by the operation of the ten-cent valve. The rotary air-distributing valve will then pass on to the dollar-port and finding a five-dollar perforation in the card will admit air to operate the clutch of the dollar-valve and move it five spaces toward the right, or six in all from its original zero position. During these movements of the ten-cent and dollar change-making valves no carrying to the next valves will take place, as the bull-teeth 193^a and 193^b will have passed the star-wheels 192^a and 192^b and will not again become operative until the next revolution of the valves. The rotary air-distributing valve having passed over all the purchase-perforations made in the bill, the change-making valves will stand in the position shown in Fig. 43. In the cents-valve there will be three perforations representing five cents, two cents, and one cent, coinciding with the ports leading to the coin-cylinders. In the tens-of-cents there will be two perforations representing twenty cents each opposite the ports leading to the coin-cylinders. In the dollar-valve there will be three perforations representing two dollars and two one dollar, or a total of four dollars, and in the ten-dollar valve there will be one perforation opposite the port leading to the tens-of-dollars coin-cylinder, and there will be delivered from the coin-cylinders the sum of the amounts represented by the perforations in the several valves, or fourteen dollars and forty-eight cents, the difference between twenty dollars, the amount received, and five dollars and fifty-two cents, the amount of the purchase. If the clerk is given five dollars in payment for purchases amounting to four dollars and twenty-five cents, he will punch the circle in the card on the received side representing five dollars and the circles on the purchase side representing four dollars, twenty cents, and five cents. Then as air is admitted through the distributing-valves the dollar-valve, or the third one of the series, will be moved five spaces toward the left, or until the port therein representing five dollars is opposite the normal zero position of the valve. Then as air is admitted successively to the cent and tens-of-cents valves they will be rotated and the first one of the series moved five spaces toward the right, or until one of the five-cent ports is opposite the normal zero position of this valve. In turning to this position the cents-valve bull-tooth will move the tens-of-cents valve one step toward the left, and this valve will also be moved two additional steps toward the left to indicate the twenty-cent purchase. When this has been done, a fifty-cent port and one of the twenty-cent ports will be opposite the normal zero position of the valve. During the movement of the tens-of-cents valve its bull-tooth will move the dollar-valve one step toward the right, and to indicate the four-dollar purchase the dollar-valve will be moved four additional spaces toward the right, returning the valve to its zero position. The calculation having been completed, the dollar-valve will stand at zero, the tens-of-cents valve will have a fifty-cent port and a twenty-cent port coinciding with the passages leading to the coin-cylinders, and the cent-valve will have a five-cent port communicating with its coin-cylinder passage or tube, whereupon a fifty-cent piece will be discharged from its coin-cylinder, and the combination of the twenty-cent and five-cent port admitting air through the twenty-five-cent valve will cause the discharge of a twenty-five-cent piece from its coin-cylinder, making seventy-five cents in all, the difference between five dollars received and four dollars and twenty-five cents, the total of the items of purchases.

The registering mechanism.—In connection with the above-described mechanism I prefer to provide a registering device, Figs. 30

and 31, for indicating the sum of all the purchases for which the machine is operated. I therefore provide a series of shafts 202, 202^a, 202^b, 202^c, and 202^e supported within a suitable casing 203 and provided with a series of ten-tooth star-wheels 204, driven step by step by ratchets 205 from corresponding star-wheels 206 on the shafts 160, 162, and 163. The star-wheels 204 and 206 being of the same size and having the same number of teeth, the revolution of the change-making valve-shafts in one direction, as when adding the items of purchase, will impart a corresponding movement to the register-shafts; but when the valves are moved in the opposite direction to indicate the amount received or the deposit the ratchet-pawls will slip over the teeth of their wheels, and no movement of the registers will take place. Retarding-pins 205 are supported above the star-wheels and arranged to engage their peripheries, being held in yielding contact therewith by springs 206. These pins prevent premature movement of the star-wheels in either direction. The register-shafts, except the first one, are all provided with star-wheels 207 and bull-teeth 208 engaging the said wheels to effect the carrying operation in the well-known manner. Arms 209 are pivoted beneath the star-wheels and adapted to engage the hubs of the same and of the bull-teeth, and said arms are also connected to the bars 196, (see Fig. 31,) so that when the change-making valve-clutches are operated each register star-wheel will be thrown out of connection with the preceding star-wheel. The register-shafts are provided with counters 210, bearing figures, as usual, from "0" to "9" and visible through peep-holes 211, normally concealed by a cover 212. (See Fig. 38.)

To disengage the star-wheels 207 from the bull-teeth 208 and allow the register-shafts and counters to be turned back to zero, I provide a rock-shaft 213, (see Figs. 31 and 38,) having an operating-handle 214 and a series of cams 215, which engage the ends of shafts 216, that are in line with the shafts 185 and move the same lengthwise to oscillate the arms 209 when the shaft is rocked. Springs 217 return the shafts 216 to their normal position, and a spring 218 oscillates the shaft 213 back to its normal inoperative position. When the arms 209 have been operated to disengage the bull-teeth from the register star-wheels, the operator grasping the milled wheels 219 can rotate the register-shafts back to zero. The shaft 202^e, however, being the fifth one of the series and having no connection with a coin-changing valve-shaft, is operated by another mechanism. In Fig. 41 I have illustrated this mechanism, which consists of a bell-crank 220, pivotally supported in the casing 203 and having one arm in the path of a cam on the shaft 213 and its other

arm forked and adapted to straddle the shaft 202^a and move its star-wheel against the tension of the spring 221 out of engagement with the bull-tooth of the next preceding shaft.

Mechanism for returning the change-making valves to zero.—Upon the shafts 160, 161, 162, and 163 star-wheels each having ten teeth are secured. (See Figs. 30, 31, 33, and 34.) These wheels are each provided with ratchet-wheels 223, having nine teeth of uniform length and one long tooth 224. A bar 225 has arms 226, carrying pawls 227 and 228, which engage the teeth of the ratchet-wheels and are held against pins 229 by springs 230. The bar 225 is supported at each end on arms 231, pivoted at their lower ends on the machine-base, and one of them has a centrally-arranged antifriction-roller 232 normally in engagement with a star-wheel 233, being held in contact therewith by a spring 234. The space 235 between two of the star-teeth being deeper than between the others allows the dogs 227 and 228 to move out of the path of the ratchet-teeth at one point in the revolution of the star-wheel. The mechanism is adjusted so that when the long teeth 224 are in position to be engaged by their pawls the antifriction-roller 232 will enter the deeper space 235 in the star-wheel, and as each long tooth 224 is arranged to be in the path of its pawl only when the change-making valve connected with that tooth is at zero it follows that if no movement of the valve has taken place from its normal zero position the pawl of the return to zero mechanism will slide over the long tooth 224 of its ratchet-wheel without operating it and the valve will consequently not be moved, but will remain stationary until operated to deliver a coin. If a valve has been moved, the pawls will engage its wheel and set the valve again at zero. The revolution of the star-wheel 233 will oscillate the bar 225, and to operate the said star-wheel I provide a rack-bar 236 in engagement with a pinion 237 on the shaft of said star-wheel and having a ratchet connection 238 with said wheel. (See Figs. 34 and 36.) A lever 239 is pivotally connected with the rack-bar 236 and supported at 240 in the frame of the machine and provided with a link 241, which connects its upper end with a crank 242 on a shaft 243, having a crank 244 connected by a hooked arm 245 with a pin 246 on the air-controlling valve-lever 11, so that when this lever is thrown to the position shown in Fig. 6, Sheet 5, the change-making valves which have been used in making change will be returned to their zero position.

The quarter-valve.—In a machine of this kind it is desirable to provide means for delivering a silver quarter or twenty-five-cent piece with a single operation; but as I have found the use of a valve for this purpose in connection with the other coin-changing

valves would necessitate a departure from the fixed tens ratio maintained between all of these valves and would tend to interrupt their operation and the proper delivery of their coins I have preferred to provide an independent device for this purpose. In Figs. 44 and 45 I have illustrated the quarter or twenty-five-cent-piece valve in detail. 247 is a suitable casing wherein the valve mechanism is arranged. In this casing are chambers 248, 249, and 250, each having a diaphragm 251 and a bushing 252, provided with inlet-ports 253. Beneath the diaphragms are valves 254, 255, and 256, and ports 257 lead into the space beneath said diaphragms. Air-passages 258 are provided around the walls of the bushings, communicating with the ports therein. The valves 254 and 256 are also provided with chambers 259, separated from the space beneath the diaphragms and communicating with tubes 260 and 261, which lead, respectively, to the double ten and five cent coin-cylinders. The middle valve 255 communicates with a tube 262, which leads to the quarter or twenty-five-cent-piece coin-cylinder. An air-passage 263 connects the valve 254 with the chamber 249 above the diaphragm. An air-passage 264 leads from the chamber 248 around the middle valve and communicates with an air-passage 265, which leads from the valve 255 to the valve 256. The valves 254 and 256 move vertically to expose the ports leading to the pipes 260 and 261 and are normally held in their closed position by springs 266, and the valve 255 moves downward to expose the port leading to the pipe 262 and is normally held closed by a spring 267. An air-passage 268 leads from the chamber 250 around the middle valve and communicates with the chamber 249 and intersects the passage 263. The tube 178 leads from the five-cent port of the cents change-making valve to the chamber 248, and a similar tube 180^a leads from the twenty-cent port of the ten-cent change-making valve to the chamber 250. When therefore the cents change-making valve is set to deliver a five-cent piece, the air will pass through the tube 178, the chamber 248, the passages 264 and 265, raise the valve 256 and pass out through the tube 261 to a five-cent coin-cylinder. To deliver two ten-cent pieces, the ten-cent change-making valve will be set to allow the air to pass through the tube 180^a to the chamber 250, thence through the passages 268 and 263 to the valve 254 and the tube 260, and from thence to the double ten-cent coin-cylinder. At the same time the air will flow into the chamber 249 and open the valve 255; but as there is no air in the passage 265 there will be no delivery of the twenty-five-cent piece. To deliver a quarter or twenty-five-cent piece when the bill is punched 65 through the twenty-cent and five-cent circles,

the air entering through the tube 178 from the cent-valve will flow around through the passage 264; but as the air will be in the chamber 250 also the valve 256 will not be opened and the passage to the five-cent coin-cylinder will be closed. The air entering the tube 180^a from the ten-cent valve will flow through the passage 268 and 263 to the valve 254; but as the air will be in the chamber 248 this valve will remain closed also and the passage to the double ten-cent coin-cylinder cut off. The entrance of air from the passage 268 into the chamber 249 will, however, depress the valve 255 and open the port leading to the tube 262 and the twenty-five cent or quarter cylinder, whereupon the air will flow therethrough and a twenty-five-cent piece will be discharged. The ports 257 allow the exhaust of any air which may leak around the valves and escape into the spaces beneath the diaphragms.

Illustration of use of twenty-five-cent-piece valve.—If the clerk is given a fifty-cent piece in payment for a purchase of twenty-five cents, the tens-of-cents valve will be moved 90 five spaces toward the right to indicate the deposit of fifty cents. Then the cents-valve will be moved five spaces toward the right to indicate the five-cent purchase and in so doing will turn the tens-of-cents valve one step 95 back or toward the left, and the twenty-cent purchase will cause this same valve to be turned two additional steps toward the left, or until one of the twenty-cent holes is opposite the zero position of the valve. The combination of this twenty-cent hole in the tens-of-cents valve and the five-cent hole in the cents-valve will admit the air to the twenty-five-cent valve and cause the delivery of a twenty-five-cent piece from its coin-cylinder.

The coin-cylinders.—At the forward end of the machine I provide a series of horizontal air-cylinders 272 and 272^a, arranged in banks across the machine, Figs. 4, 60, and 61, the row 272^a being in the rear and above the level 100 of the row 272, and all of them supported upon suitable plates 273. The air-cylinders are connected with the tubes leading from the change-making valve-ports and are provided with pistons 274, having springs 275, which normally hold the pistons in a retracted position within the cylinders. At their forward ends the pistons are connected to slides 276, which operate in the bottom of vertical coin-cylinders 277 and have holes 278 of 115 different diameter, according to the size of the coins in the cylinders. These slides operate across the bottoms of the cylinders in the usual way to eject coins therefrom into the trays 279 and 280. The coin-cylinders are 120 preferably mounted on frames 281, pivotally supported at 282 and adapted to be swung to an inclined position and supported by pins 283 in such position. The coin-cylinders are 125 preferably divided vertically into two sec-

tions, the rear half being secured to the frame and the forward half being vertically slidable on the rear half to allow the convenient filling of the cylinders with coins, as shown in Fig. 561. There are a number of these coin-cylinders, as shown on Sheet 4, to allow single coins of the different denominations to be ejected and also to allow double coins of certain denominations to be delivered. The 10 cylinders are all of the same construction, varying only in size, and I have therefore employed but one reference-numeral for all of them, designating each cylinder by the denomination of the coin it is adapted to contain. 15 Each cylinder is provided with the usual port-holes 284, through which the coins may be seen and the number of them in the cylinder easily ascertained. When air flows through the change-making valves, it will enter the 20 proper air-cylinder and actuate the piston therein and cause the discharge of the proper coin or coins from the coin-cylinders.

The bill-receptacles.—It is desirable in a machine of this kind to provide some means 25 for giving a bill in change when a purchase is made. I therefore provide a series of bill-receptacles for the one-dollar, five-dollar, ten-dollar, and twenty-dollar bills, respectively, and being all alike I will designate them by 30 the single reference-numeral 285, Figs. 1, 3, 55, and 56. These receptacles are cylindrical in form and divided horizontally into upper and lower sections, the lower ones being mounted on suitable standards or brackets 35 286 and the upper ones having pivots 287, provided with pinions 288 and adapted to revolve a half-turn and swing down under the lower section. The bill-receptacles are arranged upon different levels, as shown on 40 Sheet 16, and the upper pair are operated by means of bell-cranks 289, which have teeth 290 to engage the pinions 288. The bell-cranks are connected to pistons 291 in cylinders 292. The lower pair of bill-receptacles 45 have their pinions operated by toothed levers 293, connected to pistons 294 of cylinders 295, corresponding to the cylinders 292 and located near them. These cylinders communicate at their lower ends with the tubes 50 leading from the bill-receptacle valves, and tubes 297 in their upper ends communicate with the tube 17 from the air-controlling valve, Fig. 1. When the air is turned on the tube 17, Fig. 9, it will enter all the cylinders 55 292 and 295 and force down those of the pistons 291 and 294 that may be raised to close the bill-receptacles, should any of them be open. This occurs during the initial operation of the air-controlling valve, and air will 60 always be admitted to the cylinders, whether any of the bill-receptacles have been opened or not.

To control the passage of air to the bill-receptacle air-cylinders, I provide a corresponding number of rotary valves 298, 298^a,

298^b, and 298^c within a suitable casing 299. These valves may be designated as the controlling-valves, respectively, for the one-dollar, five-dollar, ten-dollar, and twenty-dollar bill receptacles. The one-dollar valve 70 communicates with the tube 181^b from the corresponding port of the dollars change-making valve, the five-dollar-bill-receptacle valve communicates with the tube 178^b from the five-dollar-port of the same valve, the ten-dollar-bill-receptacle valve 75 communicates with the tube 181^c from the ten-dollar change-making valve, and the twenty-dollar-bill-receptacle valve communicates with the tube 179^c from the same change-making valve. 80 Tubes 300 and 302 lead from the one-dollar-bill-receptacle valve to its bill-receptacle and coin-cylinder, respectively, and similar tubes lead from the other bill-receptacle valves to their receptacles and coin-cylinders, and I 85 have designated these tubes by the same reference-numeral with the addition of the exponents "a," "b," and "c."

The bill-receptacle valves, as shown in Fig. 59, are tapered in form and fit correspondingly-shaped chambers 303 and are provided with ports 304 and 305, which form communicating passages, alternating as the bill-receptacle valves are rotated between the tube leading to the change-making valves 90 and the one leading from the bill-receptacle valve to the bottom of its cylinder. Springs 306 hold the bill-receptacle valves snugly against the tapered walls of the chambers 303. A finger-grip 307 is provided on the stem of each bill-receptacle valve, and an indicator 308 is also provided on said stem and adapted to move back and forth on the casting 3, which bears the words "Coin" and "Bills." The pointer is so arranged that when 105 it is opposite the word "Coin" the tubes leading to the coin-cylinders through the bill-receptacle valves will be in communication and the passage to the bill-receptacle cylinders will be cut off. As soon, however, 110 as the valve is revolved so that the indicator points to the word "Bills" then communication will be established between the change-making valve-tube and the one leading to the bill-receptacle cylinder, whereupon air 115 will be admitted to the bottom of said cylinders, or one of them, according to the position of its valve, and its piston actuated to partially revolve the movable section of the bill-receptacle and open the same to allow a 120 bill to be extracted. To close any or all of the bill-receptacles, the operator will move the air-controlling valve to admit air to the tube 17 and the upper ends of the bill-receptacle cylinders.

In the operation of the machine I prefer to set each receptacle-valve so that its receptacle will be temporarily opened to allow the extraction of the desired bill. When the change-making valves have been operated 125 130

and the change delivered, it is desirable for the air to be shut off automatically and the air-controlling valve returned to its normal inoperative position. I therefore provide a 5 plunger 310 vertically movable within a cylinder 311 and normally held in a depressed position by a spring 312. A tube 313 connects the bottom of said cylinder with the tube 63 and when air flows through the upper 10 rotary valve to the change-making valves it will enter the cylinder 310 also and force the plunger 311 up against the arm 12 and actuate the air-controlling valve to return it to its zero position.

15 A cut-off valve 314 is provided in the tube leading to the change-making valves to allow the operator of the machine to close this tube against the passage of air and prevent the discharge of coins from the coin-cylinders 20 when, for instance, it is desired to make change from the total receipts and purchases represented by two bills with one operation of the machine. In that case the operator will make the proper perforations in the bill 25 on its received and purchase sides and set the change-making valves in their proper position to deliver the change called for by this bill. Then he will close the cut-off valve and remove the bill and insert another and go on 30 with the calculation, repeating the operation described with reference to the first bill, and when the difference between the deposits and the total amount of the purchases has been ascertained the coin-cylinders will be operated to discharge the proper coin or coins in 35 change.

I claim as my invention—

1. The combination with a fluid-pressure-distributing valve, of a bill adapted to be perforated to indicate the money received and the items of purchases, and change making and delivering mechanisms controlled by the flow of pressure through the perforations in said bill to discharge the desired change.

45 2. The combination with a fluid-pressure-controlling valve, of a fluid-pressure-distributing valve, a bill adapted to be perforated to indicate the money received and the items of purchases, and change making and delivering mechanisms controlled by the flow of pressure through the perforations in said bill for discharging the desired change.

55 3. The combination with a rotary fluid-pressure-distributing valve having a series of ports representing denominations of coins, of a bill adapted to be perforated to indicate the money received and the items of purchases, the perforations coinciding successively with the ports in said valve as it revolves, and change making and delivering mechanisms controlled by the flow of pressure through the perforations in said bill for discharging the proper change.

65 4. The combination with a plate having a series of longitudinal ducts therein and ports

leading therefrom to the top and bottom of said plate, a rotary fluid-pressure-distributing valve arranged to revolve on said plate and having a series of ports representing denominations of coins adapted to coincide successively with the ports in said plate, a bill adapted to be perforated to indicate the money received and the items of purchases, the perforations in said bill coinciding with the ports in the bottom of said plate, and change making and delivering mechanisms controlled by the flow of pressure through the perforations in said bill for discharging the proper change.

70 5. The combination with a fixed plate having a series of perforations therein, of a vertically-movable plate having a series of longitudinal ducts and ports leading therefrom through the top and bottom of the plate, a bill adapted to be perforated to indicate the 75 money received and the items of purchases and fitting between said plates and clamped thereby, a rotary fluid-pressure-distributing valve arranged to operate over said movable plate and having ports representing denominations of coins to coincide with the ports in said movable plate and whereby the pressure will flow down through said movable plate and the perforated portions of said bill, and change-making and coin-delivering mechanisms controlled by the flow of pressure 80 through the perforations in said bill for discharging the proper change.

85 6. The combination with a fixed plate having a series of perforations, of a movable plate having longitudinal ducts and ports leading therefrom through the top and bottom of the plate, a bill adapted to be perforated to indicate the money received and the items of purchases and clamped between said plates, the perforations in said bill registering with the ports or perforations in said plates, a rotary fluid-pressure-distributing valve operating on said movable plate and having a 90 series of ports representing denominations or coins arranged to coincide successively with the ports in said movable plate, a second fixed plate having a series of longitudinal ducts and ports leading therefrom through the top and bottom of the plate, perforated slide-valves operating between said fixed plates, a second rotary valve having ports to coincide with the ports in the bottom of said second fixed plate, and change making and delivering mechanisms controlled by the flow 95 of pressure through the perforations in said bill and the ports in said valves, substantially as described.

100 7. The combination with an air-distributing valve, of an upper rotary distributing valve having a series of ports representing denominations of coins, a movable plate having a series of longitudinal ducts and ports leading therefrom through the top and bottom of said plate, a fixed plate having a series 105

of perforations, a bill adapted to be perforated to indicate the money received and the items of purchases and clamped between said fixed and movable plates, the perforations in said bill coinciding with the ports in said plates, a second fixed plate having a series of longitudinal ducts and ports leading therefrom through the top and bottom of said plate, perforated slide-valves operating between said fixed plates, a lower rotary valve having ports to coincide with the ports in the bottom of said second fixed plate, change-making and coin-delivering mechanisms made operative by the flow of air through the ducts in said movable plate, and mechanism normally inoperative and rendered operative by the flow of air through said lower rotary valve for operating said change-making and coin-delivering mechanisms.

20 8. The combination with an air-controlling valve, of a fixed plate having rows of perforations extending lengthwise thereof on each side of the center, a movable plate having a corresponding number of longitudinal ducts and ports leading therefrom through the top and bottom of the plate, said ports and ducts representing denominations of coins, a bill adapted to be perforated to indicate the money received and the items of purchases and clamped between said plates, the perforations in the bill coinciding with the ports in said plates, an upper rotary valve having a series of ports arranged to coincide successively with the ports in said movable plate, a second fixed plate having a series of longitudinal ducts with ports leading therefrom through the top and bottom of the plate, slide-valves having each a single transverse row of perforations arranged to coincide with the ports in said fixed plates, a lower rotary valve having ports to coincide with the ports in the bottom of said second fixed plate, mechanism for operating said valves, change-making valves normally inoperative, mechanism connected with the ducts in said fixed plate for temporarily rendering said change-making valves operative, and mechanism normally inoperative and rendered operative by the flow of air through said lower rotary valve for operating said change-making valves.

9. The combination with a fluid-pressure-distributing valve, of a bill adapted to be perforated to represent the sum received and the items of purchases and fitting within said valve, rotary change-making valves having holes representing denominations of coins, coin-cylinders and coin-ejecting mechanisms therefor, tubes connecting said change-making valves with the perforations in said bill and said ejecting mechanisms, and mechanism whereby said change-making valves will be rotated in one direction to indicate the sum received and in the other to subtract the items of purchases and admit pressure to said

ejecting mechanisms to deliver the proper change.

10. The combination with the rotary change-making valves having holes representing denominations of coins, of a clutch mechanism for each valve, pressure-cylinders having their pistons connected with said clutches respectively, a gear mechanism for rotating said valves in either direction, mechanism for actuating said gear mechanism, a clutch connected with said gear mechanism and having a pressure-cylinder, a rotary fluid-pressure-distributing valve having ports arranged to communicate with the cylinders of said valve-clutches, a second rotary valve having ports communicating with said gear-mechanism clutch-cylinder, and a bill adapted to be perforated to indicate the cash received and the items of purchases and inserted between said rotary valves to regulate the flow of pressure through said second rotary valve, substantially as described.

11. The combination with a fluid-pressure-distributing valve, of a bill adapted to be perforated to indicate the money received and the items of purchases, a rotary change-making valve having a series of holes representing denominations of coins, coin-cylinders and coin-ejecting mechanisms therefor, tubes connecting said fluid-pressure-distributing valve with said rotary valve and said cylinder ejecting mechanism, and mechanism whereby the flow of pressure through the perforations in said bill will operate said rotary change-making valve, substantially as described.

12. The combination with a fluid-pressure-controlling valve, of fixed and movable plates the former having a series of perforations and the latter longitudinal ducts and ports leading therefrom through the top and bottom of the plate, a bill adapted to be perforated to indicate the money received and the items of purchases and clamped between said plates, a rotary valve operating on said movable plate and having a series of ports representing denominations of coins to coincide with the ports in said movable plate, a second fixed plate having a series of longitudinal ducts and ports leading therefrom, slide-valves operating between said fixed plates and having perforations to coincide with the ports therein, a second rotary valve, a revolving cam-shaft having a series of surfaces representing denominations of coins, a rock-shaft having an arm to bear on said cam-surfaces and connected with said slide-valves, and a change-making and coin-delivering mechanism connected with said shafts and controlled by the flow of pressure through said valves.

13. The combination with a fluid-pressure-distributing valve, of a bill adapted to be perforated to indicate the money received and the items of purchases, a series of rotary

change-making valves having holes representing denominations of coins, cylinders and ejecting mechanisms therefor, tubes connecting said change-making valves with said distributing-valve and said ejecting mechanisms, and mechanism whereby the flow of pressure through the perforations in said bill will cause the operation of said change-making valves and admit pressure to said ejecting mechanisms to discharge the proper change, substantially as described.

14. The combination with an air-distributing valve, of a bill adapted to be perforated to indicate the money received and the items of purchases, a series of loosely-mounted rotary change-making valves having holes representing denominations of coins, clutch mechanisms for temporarily locking said valves independently of one another, tubes connecting said clutch mechanisms with said air-distributing valve, coin-cylinders and ejecting mechanisms therefor, tubes connecting said change-making valves with said ejecting mechanism, mechanism for operating said valves, means for controlling said operating mechanism and tubes connecting said controlling means with the perforations in said bill, substantially as described.

15. The combination with a fluid-pressure-distributing valve, of a bill adapted to be perforated to indicate the money received and the items of purchases, a shaft provided with a series of cam-surfaces representing denominations of coins, mechanism operatively connecting said cam-shaft with said pressure-distributing valve, and change-making and coin-delivering mechanisms operatively connected with said cam-shaft and with said valve, substantially as described.

16. The combination with a reciprocating cross-head, of a cam-shaft having a series of cam-surfaces representing denominations of coins, a rock-shaft having an arm arranged to travel over said cam-surfaces and connected with said cross-head, and change-making and coin-delivering mechanisms connected with said cam-shaft and said rock-shaft.

17. In a change-making machine, the combination with a revolving shaft and a series of cam-surfaces thereon representing denominations of coins, of a rock-shaft, an arm slidably mounted thereon and having an anti-friction-roller to engage the surfaces of said cams, mechanism for moving said arm back and forth on said rock-shaft, and a fluid-pressure device for holding said anti-friction-roller against the surfaces of said cams during a portion of the revolution of said cam-shaft.

18. The combination with a revolving cam-shaft having surfaces representing denominations of coins, of a rock-shaft, an arm mounted thereon and arranged to bear upon said cam-surfaces, means for moving said

arm lengthwise of said cam-shaft, mechanism for revolving said cam-shaft, and valves operatively connected with said cam-shaft and having holes representing denominations of coins, and a suitable carrying mechanism.

19. The combination with a series of rotary valve-disks having holes extending therethrough and provided with a carrying means and mechanism for rendering said carrying means temporarily inoperative, of a cam-shaft having a series of surfaces, mechanism for revolving said shaft in either direction, and mechanism connecting said shaft and valves for rotating the latter.

20. In a change-making machine, a series of rotary disk valves having holes arranged in concentric circles and representing denominations of coins, said holes communicating as the valves revolve, with ports contiguous thereto, and a carrying mechanism for said valves.

21. In a change-making machine, a series of rotary valves having holes representing denominations of coins, and mechanism for operating said valves in one direction to indicate the cash received and in the opposite direction to add the items of purchases, substantially as described.

22. In a change-making machine, a series of rotating disks having holes representing denominations of coins, a carrying mechanism for said disks, means for temporarily rendering said carrying mechanism inoperative, and mechanism for rotating said disks in one direction to indicate the cash received and in the opposite direction to add the items of purchases, substantially as described.

23. The combination with rotary change-making valves having a series of holes representing denominations of coins and a carrying mechanism for said valves, of mechanism for rotating said valves to indicate the cash received, for the purpose specified.

24. The combination with a series of rotary valves having a series of holes therein arranged in concentric circles, fluid-pressure tubes leading to and from said valves and communicating with said holes as said valves are revolved, and a delivering mechanism connected with said tubes.

25. The combination with a series of flat valve-disks having holes extending therethrough, a carrying mechanism for said valves, fluid-pressure tubes leading to and from said disks and communicating with said holes as said disks revolve, and a delivering mechanism connected with said tubes.

26. The combination with the rotary valves having a series of holes arranged in concentric circles therein, there being nine radial rows of holes around the circumference of each valve, a carrying mechanism for said valves, fluid-pressure tubes leading to and

from said valves and communicating with said holes as the valves revolve, and a delivering mechanism.

27. The combination with the rotary valves having a series of holes therein and a carrying mechanism for said valves, and means whereby said carrying mechanism is rendered inoperative to allow the movement of a valve independently of the preceding one, of mechanism for operating said valves, fluid-pressure tubes leading to and from said valves and communicating with the holes therein, and a delivering mechanism.

28. The combination with the rotary change-making valves, having a series of holes representing denominations of coins and arranged in concentric circles, there being nine radial rows around the circumference of each valve, and a carrying mechanism for said valves, and means for temporarily rendering said carrying mechanism inoperative to allow the movement of one valve independently of the preceding one, of mechanism for operating said valves, and fluid-pressure tubes leading to and from said valves and communicating with the holes therein, and a delivering mechanism, substantially as described.

29. The combination with a series of loosely-mounted valve-disks having a series of holes representing denominations of coins and a carrying mechanism for said disks, of a mechanism for operating said disks, and fluid-pressure tubes leading to and from said disks and communicating with said holes as the disks revolve, and coin-cylinders having ejecting mechanisms connected with said tubes.

30. The combination with the rotary change-making valves having holes representing denominations of coins, of a carrying mechanism, mechanism for rendering said carrying means inoperative to allow the movement of one valve independently of a preceding one, mechanism for operating said valves in either direction, fluid-pressure tubes communicating with the holes in said valves, and a delivering mechanism, substantially as described.

31. The combination with a rotary valve having holes representing denominations of coins and provided with a carrying mechanism and means for rendering it temporarily inoperative, of a cam-shaft having surfaces representing denominations of coins, mechanism connecting said cam-shaft and said valves for revolving the latter in either direction according to the direction of movement of said shaft, for the purpose specified.

32. The combination with the rotary change-making valves having a series of holes representing denominations of coins and a carrying mechanism for said valves and means for rendering said carrying mechanism temporarily inoperative to allow a valve

to be moved independently of its preceding valve, of mechanism for operating said valves in either direction, fluid-pressure tubes connected with the holes in said valves as they are revolved, a delivering mechanism, and a return-to-zero mechanism provided in connection with said valves.

33. The combination with the rotary change-making valves having holes representing denominations of coins, a carrying mechanism for said valves, mechanism for temporarily rendering said carrying mechanism inoperative to allow one of said valves to be moved backward independently of the preceding one, coin-cylinders having air-cylinders and pistons, means for operating said valves in either direction, and air-tubes leading through the holes in said valves to said air-cylinders, substantially as described.

34. The combination with the rotary change-making valves having holes representing denominations of coins, a carrying means for said valves, mechanism for temporarily rendering said carrying means inoperative, means for operating said valves in either direction, means for rendering said carrying means operative for all said valves, fluid-pressure tubes communicating with the holes in said valves as they revolve, and a coin-delivering mechanism, substantially as described.

35. The combination with the rotary change-making valves, of a carrying mechanism, means for temporarily rendering the carrying mechanism for either valve inoperative to allow that valve to be turned backward independently of the preceding one, and mechanism for returning said carrying means to its normal operative position.

36. The combination with the rotary change-making valves each having a series of holes representing denominations of coins, of a carrying means, mechanism for rendering the carrying means for each valve inoperative to allow that valve to be turned backward independently of the preceding one, mechanism for operating said valves in either direction, fluid-pressure tubes communicating with the holes in said valves, a coin-delivering mechanism, and a registering mechanism connected with said valves.

37. The combination of the rotary change-making valves having a series of holes representing denominations of coins, there being four valves representing respectively cents, tens of cents, dollars, and tens of dollars, a carrying means for said valves, means for temporarily rendering said carrying means inoperative, with means for operating said valves in one direction to indicate the cash received and in the other direction to subtract the items of purchases, fluid-pressure tubes leading to and from the holes in said valves, and a coin-delivering mechanism.

38. The combination with the rotary

change-making valves having a series of holes representing denominations of coins and arranged in concentric circles and in nine radial rows around the circumference of each 5 valve, the first valve representing cents, the second tens of cents, the third dollars, and the fourth tens of dollars, a quarter or twenty five-cent-piece valve having tubes connecting it with the five-cent and twenty-cent holes in 10 said rotary valves, a carrying means for said rotary valves, means for operating said rotary valves, fluid-pressure tubes leading to and from the holes in said rotary valve, and a coin-delivering mechanism.

15 39. The combination with the rotary change-making valves having a series of holes therein representing denominations of coins and provided with a carrying mechanism, means for operating said valves in either 20 direction, means for rendering said carrying mechanism temporarily inoperative, coin-cylinders having coin-ejecting mechanisms, an air-distributing valve, tubes leading therefrom to said change-making valves and from 25 said change-making valves to said coin-ejecting mechanisms, and means for controlling the flow of pressure through said distributing-valve.

40. The combination with the rotary 30 change-making valves having holes representing denominations of coins, said holes being arranged in concentric circles and in nine radial rows in the surface of each valve, carrying means and mechanism for rendering 35 the same inoperative to allow a valve to be turned backward independently of the preceding one, means for operating said valves in either direction, coin-cylinders having ejecting mechanisms, and fluid-pressure tubes 40 communicating with the holes in said valves and leading to said coin-ejecting mechanisms, substantially as described.

41. The combination with a series of coin-cylinders and the coin-ejecting mechanism 45 thereof, of fluid-pressure tubes leading to said coin-ejecting mechanism, and rotary valves having perforations controlling the admission of fluid-pressure to said tubes and the delivery of coins from said cylinders, 50 substantially as described.

42. The combination with the cylinders, of ejecting mechanisms thereof, fluid-pressure tubes leading to said ejecting mechanisms, and change-making mechanism where- 55 by the admission of fluid to said tubes and said ejecting mechanisms is controlled to regulate the delivery of the articles from said cylinders.

43. The combination with the coin-cylinders 60 and the coin-ejecting mechanisms thereof, of fluid-pressure tubes leading to said ejecting mechanisms, a bill adapted to be perforated to indicate the money received and the items of purchases, a fluid-pressure-dis- 65 tributing valve wherein said bill is inserted,

and change-making mechanisms controlled by the position of the perforations in said bill for admitting air to said coin-ejecting mechanisms, substantially as described.

44. The combination with the rotary 70 change-making valves, of an air-distributing valve, a bill adapted to be inserted into said air-distributing valve and perforated to indicate the money received and the items of purchases, coin-cylinders having an ejecting 75 mechanism, tubes connecting said change-making valves with said distributing-valve and with said coin-ejecting mechanisms, a fluid-pressure-controlling valve, and mechanism operatively connected with said controlling-valve for returning said change-making valves to zero.

45. The combination with a fluid-pressure-distributing valve, of a bill adapted to be inserted therein and perforated to indicate the 85 money received and the items of purchases, of change-making mechanisms and means for operating the same, fluid-pressure tubes connecting said operating means with said distributing-valve, a fluid-pressure-controlling 90 valve, and means for automatically closing said fluid-pressure valve, substantially as described.

46. In a change-making machine, the combination with the paper-money receptacles 95 having pivoted covers and an operating mechanism therefor, of controlling-valves and fluid-pressure tubes leading through said valves to said operating mechanism, substantially as described.

47. The combination with the fluid-pressure-distributing valves, of a bill adapted to be perforated to indicate the cash received and the items of purchases, fluid-pressure-transmitting tubes, change making and delivering mechanisms controlled by the flow of pressure through the perforations in said bill, paper-money receptacles having covers normally closed and an operating mechanism therefor, and fluid-pressure tubes communicating with said change-making mechanisms, and valves for controlling the admission of pressure to said operating mechanism.

48. The combination with a fluid-pressure-distributing valve, of a bill adapted to be perforated to indicate the cash received, a series of rotary valves having holes representing denominations of coins, coin-cylinders and ejecting mechanisms thereof, pressure-tubes connecting said rotary valves with said pressure-distributing valve and said ejecting mechanisms, and mechanism whereby the flow of pressure through the perforations in said bill will operate said rotary valves and actuate said ejecting mechanisms to discharge a coin or coins from said cylinders, substantially as described.

49. The combination with the rotary change-making valves having holes representing denominations of coins and a suitable 130

- carrying means, of mechanism for operating said valves in either direction, mechanism for rendering the carrying means of each valve inoperative to allow that valve to be turned backward independently of the preceding one, a coin-delivering mechanism, a registering mechanism connected with said valves, and means whereby said registering mechanism will be operated when said valves are turned in one direction and rendered inoperative when said valves are turned in the opposite direction, substantially as described.
50. The combination with the rotary change-making valves having holes representing denominations of coins, of a casing inclosing said valves and having a fluid-pressure passage on one side of said valves adapted to communicate with the holes therein as said valves are revolved, and a series of ports on the other side of said valves, there being a port for each denomination of coin, coin-cylinders having ejecting mechanisms operatively connected with said ports respectively, a fluid-pressure-distributing valve, a bill adapted to be perforated to indicate the cash received and the items of purchases, a gear mechanism for rotating said valves in either direction, mechanism for actuating said gear mechanism, a clutch connected with said gear mechanism and having a pressure-cylinder, fluid-pressure tubes connecting said distributing-valve with said clutch-cylinder and with said fluid-pressure passage, and a valve arranged to cut off the flow of pressure from said distributing-valve to said passage to allow more than one complete operation of said change-making valves without admitting pressure to said coin-cylinder ejecting mechanisms, substantially as described.
51. The combination with a coin-cylinder and a coin-ejecting device, of a fluid-pressure cylinder having its piston connected with said ejecting device, and means having perforations representing denominations of coins for controlling the admission of pressure to said cylinder.
52. The combination with a bill-receptacle having a suitable cover, of a fluid-pressure cylinder having its piston operatively connected with said cover, and means for controlling the admission of pressure to said cylinder, for the purpose specified.
53. The combination with a coin-cylinder and a coin-ejecting device therefor, of a fluid-pressure cylinder having its piston operatively connected with said ejecting device, a bill-receptacle having a cover, a fluid-pressure cylinder having its piston operatively connected with said cover, and means for controlling the admission of pressure to said fluid-pressure cylinders and regulating the discharge of coins from said coin-cylinder and opening and closing said bill-receptacle, substantially as described.
- In witness whereof I have hereunto set my hand this 1st day of November, 1905.
- JOSEPH N. WARNER.
- Witnesses.
- RICHARD PAUL,
C. MACNAMARA.
